George H. Johnson,
By Thomas G. Orwig, Atty.

UNITED STATES PATENT OFFICE.

GEORGE H. JOHNSON, OF JAMAICA, IOWA.

WAGON END-GATE.

SPECIFICATION forming part of Letters Patent No. 479,810, dated August 2, 1892.

Application filed August 15, 1891. Serial No. 402,709. (No model.)

To all whom it may concern:

Be it known that I, GEORGE H. JOHNSON, a citizen of the United States of America, residing at Jamaica, in the county of Guthrie 5 and State of Iowa, have invented a new and useful Wagon End-Gate, of which the following is a specification.

My invention relates to that class of end-gates which are adapted to be supported in an 10 approximately horizontal position, as required to adapt it for use as a shoveling-board.

My object is to provide means for maintaining a tight joint between the rear end of the 15 bottom of the wagon-bed and that portion of the end-gate in juxtaposition thereto.

My invention consists, primarily, in the construction of a locking device adapted to connect the end-gate with both sides of the wagon-bed isochronously by the manipulation 20 of a single lever, and also in the construction of an elbow-joint adapted to support the end-gate at a slightly-upward incline from the bottom of the wagon-bed to produce a shoveling-board, and in certain other features of 25 construction, as hereinafter set forth, pointed out in my claim, and illustrated in the accompanying drawings, in which—

Figure 1 is a side elevation of the rear end portion of a wagon-box of common form, showing 30 my end-gate applied thereto in a closed and locked position. Fig. 2 is a rear end view of the same; and Fig. 3 is a side elevation of the same in an open position supported as required to be used as a shoveling-board.

Referring to the accompanying drawings, A designates a wagon-box of common form having a bottom A², to the under side of which is attached a wooden brace A³. Metal plates A⁴, having a convex outer edge and a circular perforation in the central portion thereof, are attached to the rear upper corners of the box and project rearwardly beyond the vertical plane thereof, and the wooden brace A³ has two metal plates B fixed to its under side, 45 each having a slotted extension B², which curves upward therefrom, and portions of the said brace in juxtaposition to the said slots are removed thereby, forming the opening B³.

C is an end-gate and shoveling-board of 50 common form. It is attached to the wagon-bed by means of an elbow-joint at each side thereof formed by a metal arm D, pivotally

connected to the bed of the wagon in such a manner as to be movable in a complete circle, a similar arm having a slot in its one end connected with the free end of the member D by means of a bolt D³, extended through it and through the said slot, while the remaining end of the arm D³ is pivoted to a side of the end-gate at a point lower than that to which the arm D is pivoted, as required, to allow the said arms while the end-gate is being closed to incline downward by gravity at the joint thereof, and thereby permit the end-gate to be closed.

It will be readily seen that if the important feature of pivoting the arm connected with the end-gate below that pivoted to the wagon-bed was not observed, upon closing the end-gate the bolt D³ would engage an end of the slot and prevent closing the end-gate until it was bent either upward or downward at its joint by the operator.

Two metal bars F are fixed to the rear end of the end-gate C in alignment with the plates B on the wagon-bed and project downward and enter the slotted extension B², thereby preventing all lateral movement of the end-gate, and when the gate is open, the projecting ends of the said bars enter the openings B³, as required, to allow the meeting edges of the wagon-bed and end-gate to form a tight joint.

H represents a lever fulcrumed to the central portion of the rear end of the end-gate and provided with a weight H² on its upper end, and has two arms H³ pivotally connected therewith on opposite sides of the fulcrum and extending in approximately horizontal positions and in diverse directions, the outer ends of which arms are supported by being extended through brackets J. Slots are formed in the end-gate in alignment with the metal plates A⁴ on the wagon-bed and adapted to allow the said plates to be extended therethrough.

In the practical operation of my invention, assuming that the end-gate is in an open position, it will be obvious to those familiarized with this class of devices that the gate will be firmly supported, as required, to adapt it for use as a shoveling-board, and a tight joint be maintained between it and the wagon-bed, and when it is desired to close the said gate it will be seen that the slotted ends of the

arms D² will provide a flexible joint, so that the end-gate may be easily closed and also that it may be locked by a single movement of the lever and securely held in position by 5 the weight on the end thereof.

Having thus described my invention, what I claim as new, and desire to secure by Letters Patent, is—

An improved end-gate-locking device comprising a lever pivoted to the rear end of an 10 end-gate, two arms or bolts pivotally connected with the lever on opposite sides of the fulcrum and extended horizontally in opposite

directions, perforated plates secured to the wagon-bed and adapted to receive the ends of 15 said arm-bolts, and a weight secured to the free end of the lever, adapted when the end-gate is being locked to pass a vertical line and remain at an incline and securely hold the said arms or bolts outward by means of 20 the said weight, substantially as set forth.

GEORGE H. JOHNSON.
